UNITED STATES PATENT OFFICE.

WILLIAM A. JONES, OF WEST NEW BRIGHTON, NEW YORK, ASSIGNOR TO THE BAB-COCK & WILCOX COMPANY, OF BAYONNE, NEW JERSEY, A CORPORATION OF NEW JERSEY.

STEAM-BOILER ECONOMIZER.

Application filed April 10, 1925. Serial No. 22,082.

My present invention relates to steam boiler economizers, particularly of the type in which an upper and a lower drum are connected by a bank of tubes, and will be best understood from the following description and the annexed drawing, in which the figure represents a sectional elevation of one form of Stirling boiler with an economizer embodying my invention connected thereto.

In the illustrative embodiment, the boiler has three upper steam and water drums 10, 11 and 12 and a lower water drum 13 connected by banks of tubes 14, 15 and 16 with a steam offtake at 17 leading to the superheater 18, the hot gases being supplied from a furnace 19 and being directed by the baffles shown along the tubes in the several banks to a gas outlet at the lower part of the bank 16.

In the same setting is an economizer having an upper water drum 20 and also a water drum 21 connected by a bank of tubes which are arranged in rows 22, 23, 24, 25, 26, 27, 28, 29 and 30, these tubes being arranged in a manner to be described more in detail hereafter. The gases from the boiler are directed to the upper part of the bank of tubes connecting the drums 20 and 21 by a baffle 31 and are directed thence back and forth across this bank of tubes by baffles 32 and 33 to the gas outlet 34. In the illustrative embodiment, the feed water inlet 35 supplies the boiler feed water to the drum 21 and the water, after being heated in the economizer, passes through a pipe or pipes 36 to the water space of the drum 12.

In economizers, such as that illustrated in the drawing, the water enters the lower drum 21 and flows upwards to the drum 20, the temperature of the water being gradually raised as it flows upward till, in drum 20, it approaches that of the water circulating in the boiler. Obviously, variations in the rate of feed will change the conditions in the economizer tubes, a large change in the rate of supply of feed water producing expansion or contraction in tubes connecting the drums 20 and 21 which would not arise if these tubes were part of the general boiler circulation, where the temperature of the water is substantially the same throughout the system and where changes in the rate of supply of feed water to the boiler circulation does not materially affect the temperature of the boiler water and does not, therefore, cause contrac-

tion and expansion of the boiler tubes. Hence, in such economizers, it is desirable to arrange the economizer tubes so that they can contract and expand without putting undue strain on the joints between the tubes and the drums. To this end, I provide an arrangement by which each tube will have enough curvature at at least one end to prevent an undue amount of strain through differences in expansions of the tubes in the several rows. It will be noted that each tube has a straight part for the greater portion of its length, the ends being bent so as to enter each drum radially. These straight parts are parallel and make an angle with the line connecting the centers of the drums 20 and 21, this angle, of course, being the same for all the straight parts of the tubes.

Moreover, I preferably arrange the tubes so that in each row in a plane at right angles to the axes of the drums, which is the plane seen in the drawing, a tube on one side of the center line of the bank of which the row is a part, will be a duplicate of a tube in the row and on the other side of said center line, but turned end for end. By center line of the bank, I refer to the center line of the parallel straight portions of the tubes forming the bank. This makes it unnecessary to carry as many spare tubes for replacement as would be required were the tubes bent to a different form in every row. Furthermore, by this arrangement, while the majority of the tubes have a very large bend at one end and a relatively small bend at the other, all of the tubes have sufficient bends, either at one end or at both ends, so that the tube will respond to contraction or expansion without putting undue strain on the joints between the tubes and the drums. Moreover, it will be noted that tube 22, for instance, is a duplicate of tube 30 but turned end for end. Similarly tube 23 is a duplicate of tube 29, tube 24 is a duplicate of tube 28 and tube 25 is a duplicate of tube 27. Thus the construction is greatly simplified while, at the same time, the advantages above noted as to flexibility under strain is obtained.

While the drawing shows a tube arrangement in which the tubes in a given row are all in the same plane, it will be understood that the tubes in such a row may be slightly offset from the common plane to produce a staggered effect, and that in the foregoing de-

scription and the appended claims I have used the word "row" to include not only an arrangement in which the tubes in such row are in exactly the same plane, but also an arrangement in which the tubes may be offset alternately from such common plane.

It will be understood that the arrangement which I have shown is merely illustrative and that the embodiment of my invention may be widely varied.

I claim:

1. In a fluid heater, a pair of drums of substantially equal diameter spaced apart, a bank of tubes connecting the drums and having their ends entering the drums normal to the surfaces thereof with their ends expanded into said drums, each tube of the bank having the greater portion thereof straight and parallel to the straight portions of the other tubes of the bank and extending at an angle to the line connecting the centers of said drums, each tube being curved to a substantial amount at least one end, and each tube on one side of the center line of the bank being a duplicate as to shape and length of a tube on the other side of said center line.

2. A steam boiler economizer having an upper and a lower water drum of substantially equal diameter, a bank of tubes connecting said drums, said tubes being arranged in rows extending at right-angles to the axes of the drums, each tube in each such row having the greater portion thereof straight and parallel to the straight portions of the other tubes of the row, the ends of each tube entering the drums normal to the surface thereof, the majority of said tubes having a curve at one end of a substantially greater amount than at the other end, the tubes at one side of the center line of the row having the large curves entering one drum and the tubes at the other side of said center line having the large curves entering the other drum, each tube at one side of said center line being like a tube at the other side of the center line as to length and shape, a water inlet in one of said drums, and a water outlet in the other of said drums and leading to the boiler.

3. A fluid heater having an upper and a lower drum of substantially equal diameter, a bank of tubes connecting said drums, said tubes being arranged in rows extending at right-angles to the axes of the drums, each

tube in each such row having the greater portion thereof straight and parallel to the straight portions of the other tubes of the row, and extending at an angle to the line connecting the centers of said drums, the ends of each tube entering the drums normal to the surface thereof and one end at least being curved to a substantial amount, and each tube in each such row being a duplicate as to shape and length of a tube on the other side of the center line of the bank, but turned end for end.

4. A steam boiler economizer having an upper and a lower water drum of substantially equal diameter, a bank of tubes connecting said drums, said tubes being arranged in rows extending at right-angles to the axes of the drums, each tube in each such row having the greater portion thereof straight and parallel to the straight portions of the other tubes of the row and extending at an angle to the line connecting the centers of said drums, the ends of each tube entering the drums normal to the surface thereof and one end at least being curved to a substantial amount, each tube in each such row on one side of the center line of the bank being a duplicate as to shape and length of a tube on the other side of said center line of the bank but turned end for end, a feed water inlet to said lower drum, and an outlet from said upper drum.

5. A steam boiler economizer having an upper and a lower water drum of substantially equal diameter, a bank of tubes connecting said drums, said tubes being arranged in rows extending at right-angles to the axes of the drums, each tube in each such row having the greater portion thereof straight and parallel to the straight portions of the other tubes of the row and extending at an angle to the line connecting the centers of said drums, the ends of each tube entering the drums normal to the surface thereof and one end at least being curved to a substantial amount, each tube in each such row on one side of the center line of the bank being a duplicate as to shape and length of a tube on the other side of said center line of the bank but turned end for end, a feed water inlet to said lower drum, an outlet from said upper drum, and means causing heated gases to flow downwardly over all of said tubes.

WILLIAM A. JONES.
